UNITED STATES PATENT OFFICE.

JAMES L. MCKINNEY, OF ST. LOUIS, MISSOURI.

SIGNAL.

1,271,740.

Specification of Letters Patent.

Patented July 9, 1918.

Application filed December 26, 1917. Serial No. 208,760.

To all whom it may concern:

Be it known that I, JAMES L. MCKINNEY, a citizen of the United States, residing in the city of St. Louis and State of Missouri, 5 have invented a certain new and useful Signal, of which the following is a specification.

My invention relates to improvements in signals and has reference more particularly 10 to a railway-gate signal and has for its object to provide a device which will display a warning signal when the gate is down and hide the warning signal from view when the gate is up or open.

15 A further object of the invention is to provide a signal device which is closed on all sides excepting for a window in the front face of the device thereby providing a signal capable of using a red-light which will not 20 be visible to railroad employees, but visible only to traffic approaching the closed railroad gate.

25 A still further object of my invention is to provide a signal housing having a balanced signal plate pivotally mounted therein, said housing adapted to be fixed to a railroad-gate and movable therewith so that a warning carried by the signal plate may be visible through a window when the railroad-gate is down and protected from view when 30 the railroad-gate is up or open.

With the above and other objects in view the invention consists in certain new and novel constructions, arrangements and combination of parts as will be more fully described hereinafter and finally pointed out in the claims hereto appended.

35 Referring to the accompanying drawings forming a part of this specification wherein 40 like characters of reference denote similar parts throughout the several views:

45 Figure 1, is a front elevation in full and dotted lines of a railroad crossing gate in closed and open positions respectively, and to which is fixed my signal device.

Fig. 2, is a detail in front elevation, of the signal device as it appears when the crossing-gate is up and the warning upon the signal plate is out of view.

50 Fig. 3, is a detail, in front elevation, of the signal device as it appears when the crossing gate is closed or lowered and the warning upon the signal plate is in view.

55 Fig. 4, is a detail, in rear elevation, of the signal device showing it fixed to a railroad crossing-gate.

Fig. 5, is a front elevation of the signal device with the housing in cross-section.

Fig. 6, is a vertical sectional view of the signal device taken on line X—X of Fig. 4, 60 looking in direction of the arrow.

Referring to the drawings the reference character 1, designates an ordinary type of railroad crossing-gate arm.

In carrying out the aim of my invention, 65 I employ a suitable metallic housing 2 which is fixed to the gate-arm 1 by means of suitable fastening means 3. The front face of the housing is provided with a suitably shaped and sized sight opening 4. The rear 70 face of the housing 2 is provided in its upper half with a suitably shaped door 5 hinged, as at 6, to the back face of the housing. The door is held in a closed position 75 by means of a suitable fastening device 7. The upper part of the door 5 is provided with a plurality of suitable openings 8 to permit heat to escape from the interior of the housing and to provide air thereto to enable a lamp to burn therein.

80 The opening 4 in the front face of the housing 2 is preferably closed by means of a glass designated 9.

Pivottally supported by means of a suitable shaft 10 within the housing 2 is a suitable signal plate 11. One end of the shaft 10 is supported by means of the bearing 10' while the opposite end of the shaft 10 is supported by means of a suitable adjusting screw 13, as clearly shown in Fig. 6.

85 The upper end 12 of the signal plate 11 is preferably provided with a suitable warning, such for instance as the word Stop, which is stamped in section 12 of the signal plate 11. Anv suitable warning characters may 90 be formed in this plate section 12 and covered with a red glass, or celluloid facing 14.

95 A suitable lamp 15 is supported by means of the signal plate 11 to the rear of the signal plate section 12 thereby permitting light 100 from the lamp to shine through the warning plate section 12 of the signal plate 11, as is manifest.

The lower edge of the signal plate 11 is 105 provided with a suitable balance weight 16, to hold the warning plate section 12 of the signal plate 11 in its upright position at all times, as clearly shown in Figs. 5 and 6.

110 The operation of the signal device is as follows:

When the gate-arm 1 is down or in its horizontal position, the warning plate sec-

tion 12 of the signal plate 11 is directly to the rear of the opening 4 in the front face of the housing 1, thereby displaying a warning signal in red, to all approaching traffic, 5 such as vehicles, pedestrians, etc.

As the gate-arm is being raised, it will be observed, that the opening 4 in the face of the housing 1, gradually moves to one side of the warning plate section 12 of the 10 signal plate 11, thereby entirely hiding the warning plate section 12 from view when the gate-arm 1 is in its uppermost or open position, as clearly illustrated in Figs. 1 and 2. It will be observed that the housing 15 1 moves with relation to the signal plate which stands still in a balanced position, thus it will be seen that the warning signal is in full view of approaching traffic when the gate-arm is down or closed and completely hidden from view when the gate-arm 20 1 is raised or in an upright position.

The many advantages of a signal as herein described will readily suggest themselves to those skilled in the art to which it appertains.

The exact construction illustrated in the drawings is not essential to the invention, as is manifest, and being aware that various changes may be made in the construction 30 and arrangement of parts without departing from the principle of my invention, I reserve the right to make any such changes or modifications as may fairly fall within the scope of the appended claims when 35 fairly construed.

What I claim is:

1. In combination with a railway crossing gate-arm, a signal comprising a housing having a sight opening fixed to said gate-arm, a self balanced indicator arranged inside of said housing adapted to be exposed to view through said sight opening when the gate-arm is in a horizontal position and out of alinement with said sight opening when the gate-arm is in an upright position.

2. In combination with a railway crossing

gate-arm, of a signal comprising a housing provided with a sight opening fixed to said gate-arm, means pivotally balanced within said housing, a door for said housing, a warning indicator forming a part of said balanced means, a lamp supported by said means to the rear of said warning indicator for illuminating said indicator, said warning indicator adapted to be exposed to view 50 through said sight opening to approaching traffic when said gate-arm is in a horizontal position and out of alinement with said sight opening when said gate-arm is in an upright position.

3. In combination with a railway crossing gate-arm, of a signal comprising a housing provided with a sight opening fixed to said gate-arm, a door for said housing, a signal plate pivotally arranged within said housing, a warning indicator formed at the upper end of said signal plate, a lamp supported to the rear of said warning indicator for illuminating said warning indicator, a weight fixed to the lower part of said signal plate for balancing said warning indicator, said warning indicator adapted to be exposed to view through said sight opening when the gate-arm is in a horizontal position and out of alinement with said sight 65 opening when said gate-arm is in an upright position.

4. In combination with a railway crossing gate-arm, of a housing provided with a sight-opening fixed to said gate-arm, a door for said housing, indicating means pivotally balanced within said housing, means for illuminating said indicating means, said indicating means adapted to be exposed to view to approaching traffic when said gate-arm is in a horizontal position and out of alinement with said sight opening when said gate-arm is in an upright position.

In testimony whereof, I have hereunto signed my name to the specification.

JAMES L. MCKINNEY.
